UNITED STATES PATENT OFFICE.

WILLIAM A. AUSMUS, OF CHICAGO, ILLINOIS, ASSIGNOR TO PROTECTED REFILL CORPORATION, OF CHICAGO, ILLINOIS, A CORPORATION OF ILLINOIS.

COMBINATION NOTEBOOK COVER AND STAND.

Application filed December 26, 1924. Serial No. 758,242.

This invention relates to a combination note-book cover and stand and has for its primary object the construction of an inexpensive article that may be readily set up 5 for supporting a note-book when transcribing and may be readily collapsed for covering the note-book or supporting the same when taking dictation.

Another object of the invention is the use 10 of a novel construction of clip in the combination so that the note-book will be effectively supported in the combination with an inexpensive means for holding the used leaves of the note-book in a non-obstructing 15 position.

With these and other objects in view the invention will be better understood from the following description taken in connection with the accompanying drawings, wherein:

20 Fig. 1 is a perspective view of the device in set up position.

Fig. 2 is a plan view, partly collapsed.

Fig. 3 is an edge elevation.

25 Fig. 4 is an enlarged sectional view on the line 4—4 of Fig. 2.

Fig. 5 is an edge elevation of the device collapsed to cover the note-book.

Fig. 6 is a similar view of the device collapsed to the extent of forming a stiff back 30 for the note-book.

Fig. 7 is a detailed view of a slight modification.

Again referring to the drawings illustrating one of the many constructions of my invention it will be noted that the device is formed from a plurality of sections and, for the sake of clearness, the section 1 is designated as the bottom section, section 2 is the front section and section 3 is the back 35 section. These sections are flexibly connected together in various ways such as by the flexible material 4 while the lower edge portion 5 of the front section is removably mounted in the groove 6 in the bottom section. 40 If an adjustable connection is desired there may be formed a plurality of grooves as indicated at 7 in Fig. 7. I have

illustrated a special design of clip 8 having a back 9 secured to the front section and the clamping flange portion 10. The back section 3 has secured thereto, in a suitable manner, a sheet of material defining a transversely extending edge portion 12' providing a pocket 12. This edge portion 12' of the sheet extends diagonally across the section 3 to provide a mouth and to facilitate insertion of each sheet of the note-book into the pocket as the same is turned back upon the section 3. In the use of the device the various sections may be 60 folded as illustrated in Fig. 5 to cover and protect the note-book or they may have the relative arrangement as shown in Fig. 6 to provide a stiff back for the note-book when taking dictation. In transcribing, the 65 sections will be extended and set up as shown in Fig. 1 so that the note-book will be supported at the proper inclination and as the leaves are used they are folded over the device and inserted in the pocket, the 70 walls of which retain the leaves in position.

Of course, it will be understood that the sections may be formed of cheap material such as cardboard over which is arranged a covering as illustrated in the drawing 75 or may be of stamped metal or in fact formed in various ways of various materials and therefore I do not desire to be limited in any manner except as set forth in the claim.

Having thus described my invention, what I claim is:

A combination book cover and stand including a front section, a back section, a flexible connection between adjacent edge portions of the front section and the back section to permit the sections to be inclined toward each other, and a member carried by the back section defining a pocket having a mouth extending diagonally across the 85 back section.

In testimony whereof I affix my signature.

WILLIAM A. AUSMUS.
